ANCHOR

Frank W. Southard, Freeport, N. Y., assignor to
 Southard Enterprises Inc., Bellmore, N. Y., a
 corporation of New York

Application September 19, 1950, Serial No. 185,559

2 Claims. (Cl. 114—207)

1

This invention relates to anchors of the type having a stock slideable in a hole in the head of the shank which can be moved from operative to folded positions, and has for its object the provision of an improved anchor of this type. More particularly, my invention provides an improved means for moving the stock from its folded to its operative positions and for securing it in its operative position.

The improved anchor of my invention comprises a hole, preferably cylindrical, in the head of the shank in which the stock slides and turns, a projecting lug on the head, and a collar on the stock with a slot or keyway through which the lug is slideable. The lug has a locking end-portion spaced from and extending parallel to the shank leaving a space between the lug and the head for receiving the collar. The stock has the usual laterally disposed or bent end and the slot in the collar and the lug are so located with respect to each other that when the bent end points towards the arms of the anchor the collar is secured in the space between the head and the lug.

The anchor of my invention is very simple in construction and accordingly relatively easy to manufacture. The important parts of the shank and head are not weakened or encumbered with complicated parts and shapes which become fouled with rust and mud.

These and other objects of the invention will be better understood after considering the following discussion taken in conjunction with the accompanying drawings, in which:

Fig. 1 is a perspective of an anchor embodying the invention;

Fig. 2 is a side view of Fig. 1, and

Figs. 3 and 4 are enlarged views of the head portion of the shank of the anchor of Fig. 1.

The improved anchor of the invention comprises the usual arms 1 and 2, shank 3, head 4, and stock 5. The stock is slidably mounted in the round hole 6 of the shank head and has a laterally bent end 7 with a knob to prevent it from passing through the hole.

The head of the shank has an integral lug 10 with a rectangularly shaped recess 11 formed between the head and the lug. At approximately the mid-point of the stock, a flat disc-like collar 12 is permanently attached, as by welding. The collar has a slot or keyway 13 shaped to slide over the lug 12 to permit the collar to enter the

space 11 in which it may be turned to a secured position.

Fig. 1 shows the anchor with the stock 5 in its operative position. It will be noted that the depending end 7 normally holds the stock in its operative position with the collar secured in the recess 11 between the lug and the head. In order to place the stock in its inoperative folded position, as in Fig. 2, the stock is turned approximately 180° to bring the slot 13 on the collar into mating relation with the lug 10 and the stock can then be slid through the hole 6 out of its secured position.

I claim:

- 15 1. An improved anchor of the type having a shank with a head thereon, a hole in the head, and a stock which is slideable and rotatable in the hole which comprises a lug integral with the head with an end-portion spaced from the head 20 leaving a recess between the lug and head, a collar on the stock having a slot which, when the lug and slot are in coincident relation, permits the collar to slide over the lug end-portion and enter the recess, whereby turning the stock 25 sets the collar in a secured position between the head and lug in the recess preventing sliding movement of the stock in its operative position from which the stock may be removed by turning the stock to bring the lug and slot into coincident 30 relation and sliding the stock to its inoperative folded position.

2. An anchor according to claim 1 which comprises an annular collar mounted concentric with the stock which is rotatable in the recess.

FRANK W. SOUTHARD.
